VELOCIPEDE

Nolan Rhoades, Beloit, Wis., assignor to Garton Toy Company, Sheboygan, Wis., a corporation of Wisconsin

Application May 2, 1955, Serial No. 35,763

Term of patent 14 years

(Cl. D34—15)

Fig. 1

Fig. 2

Fig. 3

Fig. 4

Fig. 1 is a side perspective view of the velocipede, showing my new design.

Fig. 2 is a perspective view looking down from the back of the velocipede.

Fig. 3 is a side elevation view of the velocipede; and Fig. 4 is a plan view of the velocipede.

I claim:

The ornamental design for a velocipede, substantially as shown.
